DECANTER

Walter T. Heintze, New Canaan, Conn., assignor to Schenley Industries, Inc., New York, N.Y., a corporation of Delaware

Filed Dec. 19, 1962, Ser. No. 72,899

Term of patent 14 years

(Cl. D58—6)

I claim:

The ornamental design for a decanter, as shown.
